UNITED STATES PATENT OFFICE.

JOSEPH A. MUMFORD, OF ROSLYN, NEW YORK.

STEAM-BOILER.

SPECIFICATION forming part of Letters Patent No. 752,351, dated February 16, 1904.

Application filed April 9, 1903. Serial No. 151,769. (No model.)

To all whom it may concern:

Be it known that I, JOSEPH A. MUMFORD, a citizen of the Dominion of Canada, and a resident of the village of Roslyn, county of Nassau, State of New York, have invented certain new and useful Improvements in Steam-Boilers, of which the following is a full, clear, and exact description, reference being had to the accompanying drawings, in which—

10 Figure 1 illustrates a side elevation of a boiler embodying my invention. Fig. 2 illustrates a longitudinal vertical sectional view thereof. Fig. 3 illustrates a transverse vertical section on the line 22 of Fig. 2 and looking in the direction of the arrow.

This invention relates to that class of boilers which is known as "internally-fired" and in which the water within the boiler has continuous circulation.

20 It embodies improvements upon the boiler patented to me in and by United States Letters Patent dated April 21, 1896, and numbered 558,698.

In the practical use of boilers made as described in said patent it has been found that a portion of the hot gases or products of combustion after passing through the fire-tubes in the boiler proper pass downwardly and forwardly between the shell of the boiler and the

30 exterior casing and that as they reach the section beneath the fire-pot, where the space is contracted by the downward dip of the boiler-shell, the soot and other products of combustion having considerable gravity, lodged there and engendered corrosive action upon the shell-plates, so that after a time little leakages appeared, which still further accelerated and produced corrosive action, so that in a comparatively short time the boiler was seriously

40 injured at this part, whereas its other parts were perfectly good and capable of use for years.

Under my present invention, therefore, I modify the construction of the exterior casing, so that while all the parts of the previous construction are retained and utilized the hot gases and products of combustion are prevented from passing downwardly beneath the boiler, and there is no area of comparative quiet in which the soot and like material may

be deposited, and I also materially reduce the size or bulk and expense of the boiler as a whole and afford firm rigid support for the water-tank. This is essential, because my boilers are frequently used upon movable structures— 55 as, for example, on shipboard—and in such cases firm and rigid support for the superposed water-tank is essential.

Referring now to the drawings, A is the water-jacketed boiler proper. It may be made 60 in any preferred manner.

B is the furnace located within the end of the boiler. The shell C of the furnace-section is in this instance corrugated.

D are the fire-tubes.

E is the superposed steam and water tank.

F are the front and rear water-legs or connecting-pipes, through which the circulation of water induced by the heating takes place in a manner well known.

G is a chamber beyond the end of the boiler proper, with which the fire-tubes connect and in which the products of combustion turn backwardly upon themselves and pass forwardly again in contact with the exterior of the shell 75 of the boiler and of the steam-drum E, finally escaping through the stack H.

I and J are suitable hand-hole plates for cleansing, as well understood.

The casing K is or may be composed of a 80 series of plates (see Fig. 1) suitably connected by bolted flanges L, and they extend from about the medial line of the steam and water drum to which they are bolted downwardly to about the medial line of the boiler, as shown, 85 and at the rear end of the boiler these plates are carried downwardly, as shown at M, so as to constitute the chamber G, heretofore referred to.

It will be noted that under this present construction the products of combustion are confined in their return movement from the rear end of the boiler forwardly on their way to the stack to the chamber G and the irregularly-shaped space N and that the draft will be 95 essentially improved and likelihood of corrosion and resulting leakage reduced, indeed practically prevented, also that there are certain structural advantages in addition to those specified resulting from my construction, 100

among them the following: First, owing to the elimination of the exterior casing, such as shown in my previous patent, the size and consequent cost of the boiler as a whole and 5 also its weight are considerably reduced; second, the casing K, since it is made of sufficiently heavy and flanged plates bolted to each other and also firmly bolted to the boiler and water-drum, acts as a firm support or foundation for the drum, because it is by these plates made practically integral with the boiler proper, and is thus firmly supported against the strain to which, owing to the weight of the tank, the structure is subjected when used 10 on a moving support, as, for instance, on locomotives or aboard ship. Also by filling in the lower part of the chamber G below the lowermost fire-tube with suitable fire-clay, asbestos-cement, or equivalent material, as indicated at 15 O, Fig. 2, I provide in the lower part of said chamber a space or receptacle within which soot and other products of combustion may be deposited, which may be readily removed through the end door I, and no corrosive action 20 can arise from the deposition of this material in this place, because the asbestos-cement or other protective covering O will separate the deposited material from the boiler structure proper, so that no harm will come to it, and 25 inasmuch as the products of combustion have 30 to change their direction in this chamber G

in order to pass again forwardly there are more or less eddies formed which afford opportunity for the heavier products of combustion to drop or precipitate into the lower 35 part of the chamber G, as stated.

It will be obvious to those who are familiar with this art that modifications may be made in the details of construction of my improved boiler without departing from the essentials 40 thereof. Consequently I do not limit myself to the details described and illustrated.

I claim—

The combination with a boiler having an internal fire-box and fire-tubes of a superposed 45 water-drum, water-legs connecting the drum and the jacket of the boiler, a casing, a return flue or passage within the casing and between the boiler and drum connecting at one end with the stack, a chamber at the rear end of the 50 boiler projecting downwardly below the lowermost fire-tube and protective material within the chamber upon which the deposited products of combustion fall.

In testimony whereof I have signed my name 55 to this specification in the presence of two subscribing witnesses.

JOSEPH A. MUMFORD.
